DRILL HOLDER

Eugene F. Huot, St. Paul, Minn.

Application September 2, 1947, Serial No. 771,771

2 Claims. (Cl. 206—17)

1

This invention relates to a drill holder, which drill holder comprises a plurality of relatively movable drill-holding members, said members preferably being swingingly mounted in a casing so as to be of easy access. In using and handling drills in machine shops, particularly in larger shops where a great number of drills are handled, a great many of the drills are mislaid and lost. A workman having a set of drills often loses these drills by leaving them lying about in different places in the shop. It is desirable to have a drill holder comprising a casing or cabinet in which a plurality of drill-holding members are mounted, said casing or cabinet being of a size which can be placed in the workman's tool box or his locker and locked up while not in use.

It is an object of this invention to provide a drill holder comprising a casing preferably made of nonmetallic material, such as a plastic, a frame extending about the inside of said casing in contact with the top, bottom and side walls thereof, said casing having a hinged cover, and a plurality of drill-holding members disposed in said casing and mounted in said frame.

It is a further object of the invention to provide a drill holder comprising a generally flat casing of nonmetallic material, the same having a rear wall, top, bottom and parallel side walls, said casing being open at the side opposite said rear wall and preferably having a projecting flange of reduced thickness extending about said top, bottom and one side wall, a cover hinged along the edge of the other side wall, said cover having a flange adapted to fit over said first mentioned flange so that the outer side of said flange on the cover is preferably flush with the outer sides of said casing, a frame made from a strip of sheet material extending about the inside of said casing in contact with said top, bottom and side walls, said frame preferably having a width substantially equal to the depth of said casing, a plurality of small rods mounted in and extending between the sides of said frame adjacent the bottom of said casing, said rods being spaced upwardly and rearwardly successively, and a plurality of drill-holding members respectively swingingly mounted on said rods.

It is also an object of this invention to provide a drill holder comprising a generally flat casing of nonmetallic material, said casing having a rear wall, top, bottom and parallel side walls, a cover hinged along the edge of one side wall, a frame frictionally mounted in said casing and extending about the inside thereof in contact with said top, bottom and side walls, and a

2

plurality of drill-holding members disposed in said casing and swingingly mounted in said frame, said casing being constructed and arranged to be tightly closed by said cover.

It is still further an object of this invention to provide a drill holder comprising a frame formed of a strip of sheet metal and having top, bottom and parallel side portions, together with a plurality of drill-holding members swingingly mounted in said frame.

These and other objects and advantages of the invention will be fully set forth in the following description made in connection with the accompanying drawings in which like reference characters refer to similar parts throughout the several views and in which:

Fig. 1 is a view in front elevation of said device with the cover thereof in open position;

Fig. 2 is a vertical section taken substantially on line 2—2 of Fig. 1 with the cover in closed position;

Fig. 3 is a horizontal section taken on line 3—3 of Fig. 2;

Fig. 4 is a horizontal section taken substantially on line 4—4 of Fig. 2;

Fig. 5 is a view in front elevation of a modified form of drill holder;

Fig. 6 is a vertical section taken on line 6—6 of Fig. 5; and

Fig. 7 is a horizontal section taken on line 7—7 of Fig. 5, said sections being taken as indicated by the arrows.

Referring to the drawings a drill holder is shown comprising a casing 10. While casing 10 might be variously made, the same is of generally flat form, or in other words, its depth is small compared to its width and height. Casing 10 is preferably made of some nonmetallic material, such as one of the modern plastic compositions.

Casing 10 comprises a rear wall 10a, a top wall or side 10b, a bottom wall or side 10c, and parallel sides 10d and 10e. Casing 10 is often at the side opposite rear wall 10a. The sides 10b, 10c and 10d have an upwardly projecting flange 10f formed thereon which, as shown, is of less thickness than said walls. The side 10e of casing 10 is thickened at its front, as shown in Fig. 3, and formed with a plurality of spaced apertured lugs 10g. A cover 11 is provided which is formed along one side with a plurality of spaced apertured lugs 11a adapted to substantially fit respectively between the lugs 10g. A pintle pin 12 extends through the apertures in lugs 10g and 11a and is frictionally held in casing 10. Cover 11 is provided with a flange 11b at three sides thereof

and when the cover is closed, flange 11b fits over the flange 10f so that the outer side of flange 11b is flush with the outer sides of the walls 10b, 10c and 10d, as shown in Figs. 3 and 4. A frame 13 is provided and this is preferably formed from a strip of sheet metal, the same extending about the inside of walls 10b, 10c, 10d and 10e in contact therewith, said frame having a width substantially equal to the depth of casing 10, as shown in Fig. 2. Frame 13 is frictionally held in 10 casing 10. It will be seen that frame 13 is engaged by the lugs 10g and that the lugs 11a swing substantially in contact with the outer side of frame 13. A plurality of small rods 14 extend 15 between the sides of and are mounted in frame 13, the lowermost one of said rods being adjacent the bottom and front of casing 10 and said rods being spaced successively upwardly and rearwardly from said lowermost rod. Respectively mounted upon rods 14 for swinging movement 20 are a plurality of drill-holding members 15. Each of said drill holders comprises a piece of sheet metal forming a front portion thereof and extending to within a very short distance of the sides of frame 13. Said piece of sheet metal is 25 bent inwardly at right angles to form side flanges 15a. A bar 15b preferably of metal extends between the side flanges 15a having its top side substantially flush with the top of said member, said bar being secured to said front portion in any suitable manner, as by welding. Bar 15b is provided with a multiplicity of holes 15c. Said front portion of each of said drill holders is bent around its respective rod 14 in a substantially 30 semicylindrical portion 15d. Said drill holder or piece of sheet metal is then bent to extend rearwardly a short distance, as shown at 15e, and then is bent to extend vertically a short distance to form the rear portion 15f. Drills 16 can be placed to extend through the holes 15c and the lower ends will rest upon the portion 15e. Said drills will be prevented from motion forwardly and rearwardly by portion 15f and the front side of holes 15c. The holes 15c are of reduced size 35 in the drill-holding members 15 and as shown in Fig. 2 said drill-holding members are of successively smaller size toward the rear of casing 10. In the rearmost holder 15 the portion 15e is omitted. The drills held in said rearmost member 15 are so small that there is plenty of room for them by merely extending the rear side of the holder upwardly from the rod 14. The drill holders 15 have designations formed thereon at their front sides which are preferably formed by pressing the same outwardly in the front side of said members. The numbers of the drills are designated by the numbers in row 18. In row 19 the diameter of the drills are given. In row 20 the tap sizes of the drills are given. In row 21 the tap drill to be used with the drill is designated, and in row 22 the body drill to be used is designated.

In operation the various drills are placed in the proper places and this can conveniently be done by swinging the drill-holding members 15 forwardly out of the front of the casing with cover 11 in open position. The drill-holding members swing back into the positions shown in Figs. 2 and 3. The cover 11 can now be closed. It is pointed out that a very tight casing is produced and one which will exclude dirt and dust from getting to the interior thereof. The present invention is a great improvement upon that shown in applicant's prior Patent No. 1,930,617, granted October 17, 1933. In the structure shown

in said patent the casing which was formed of sheet metal was not tightly closed when the door B was in closed position. With the present cover and the flanges 10f and 11b and the frame 13 closely engaging lugs 10g and 11a, a very tight casing is provided. The plastic casing which can thus be made quite tight is much lighter than the metal casing shown in the patent and is of much neater form. As stated, the sides of the casings and the outer sides of the cover flange are flush. The plastic material is not so cold as the metal shown in the prior patent and the same is thus much more convenient and agreeable to handle in cold weather. Less metal is required in the drill holder and this is quite an item of expense as well as convenience since steel has been difficult to secure. The casing 13 is frictionally held in position which also makes an inexpensive and easily formed structure. Frame 13 extends about the inside of the plastic casing and acts to greatly reinforce the same so that it will not be broken. This frame therefore has the double function of supporting the drill-carrying members and also acting as a frame or reinforcement for the plastic casing.

In Figs. 5, 6 and 7 a modified form of drill holder is shown. This comprises a frame 30 made of a strip of sheet metal, the same having a top portion 30a, a bottom portion 30b and parallel side portions 30c and 30d. Top portion 30a slopes upwardly toward side 30d and merges into sides 30c and 30d respectively in curved form. A plate 31 is provided also formed of thin sheet metal and this has a rear portion 31a extending across the rear of frame 30 between sides 30c and 30d, the same having its top edge some distance from the top portion 30a. Member 31 has side portions 31b which extend along the outside of side portions 30c and 30d and are bent around the front of said side portions, as shown in Fig. 7. Plate 31 also has a bottom portion 31d which extends across the bottom portion 30b and has its edge bent over said bottom portion, as shown in Fig. 6. Small rods 32 are mounted in frame 30 and extend between the sides thereof. The lowermost rod 32 is close to the bottom in front of frame 30 and the upper rod 32 is spaced vertically and rearwardly from said lowermost rod. Drill-carrying members 33 are provided each formed of a piece of sheet metal which has a front portion 33a and side portions 33b bent substantially at right angles thereto and extending rearwardly. The lower part of said plate is bent around rod 32 in substantially semicylindrical form and is then bent rearwardly for a short distance and then upwardly for a short distance parallel to front portion 33a. A plate 33c extends between flanges 33b adjacent the top of portion 33a and is provided with a plurality of holes. A similar plate 33d extends between flanges 33b some distance below plate 33c. This plate also has a plurality of holes therethrough in vertical alignment with the holes in the plate 33c. Plates 33c and 33d have a short vertical flange 33e at their rear sides which is thus parallel to the front portion 33a. Portion 33a has numerals thereon, the top row 35 indicating the diameter of the drill in common fractions while the lower row 36 has the diameter of the drill respectively in decimals.

The drill holder shown in Figs. 5, 6 and 7 is quite simple and the frame part in which the drill-holding members are mounted is made of only two pieces. This form of drill holder is very convenient for hanging up against the wall.

The upper corner hangs nicely on a nail or pin or the holder can be hung in vertical position on a plate or strip projecting from the wall. This drill holder can also be very convenient carried in the tool box of the machinist and can thus be kept under lock or key. The structure is simple and compact and can be easily and inexpensively made.

From the above description it will be seen that I have provided a much improved structure of drill-holder. The present structure has many advantages over the structure shown in the patent and constitutes a real advance in the art. The same has been amply demonstrated in actual practice, found to be very successful and efficient and is being commercially made.

It will of course be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A drill holder having in combination, a generally flat casing of nonmetallic material, said casing having a rear wall and top, bottom and parallel side walls, and being open at the side opposite said rear wall, a cover hinged along one edge of said open side and having a flange adapted to fit over the open side of said casing so that a closed structure is formed having a smooth exterior, a frame formed of a strip of sheet metal disposed in said casing and extending about the inside of said casing in contact with the top, bottom and side walls thereof, three or more small rods extending between the sides of said frame adjacent the bottom thereof and spaced upwardly and rearwardly, drill casings swingingly mounted respectively on each of said rods and each comprising a piece of sheet metal having a front side and bent at right angles to have narrow side flanges, a bar having a plurality of holes therethrough secured to said holder adjacent the top thereof and extending between said side flanges, said front portion being bent reversely to extend about one of said rods and then being bent to extend upwardly and parallel to said front portion for some distance, said casing being suc-

50

sively of less width extending upwardly in said frame.

2. A drill holder having in combination, a generally flat casing of nonmetallic material, said casing having a rear wall, top, bottom and parallel side walls, and being open at its side opposite said rear wall, said casing along one side being thickened to provide a series of spaced apertured lugs extending throughout the length of said side, said casing having a flange of reduced thickness extending about the other three sides at the open side thereof, a cover having a series of spaced apertured lugs disposed between said first mentioned lugs, a pintle extending through all of said lugs whereby said cover is hinged to said casing, said cover having a flange extending about three sides thereof and adapted to fit over said first mentioned flange so that the outer surface of said cover is flush with the outer surface of said casing, an open frame formed of a strip of sheet metal extending about the inside of said casing in contact with the top, bottom and side walls thereof including said first mentioned lugs, said frame having a width equal to the depth of said casing and acting to reinforce said casing, a series of small rods extending between the sides of said frame adjacent the bottom thereof and spaced successively upwardly and rearwardly and a plurality of flat drill-holding members having their lower ends bent around said rods respectively to be swingingly mounted thereon disposed in said casing.
